Filed Sept. 25, 1964, Ser. No. 81,875

Term of patent 14 years

(Cl. D58—5)

FIG.1

FIG.2

FIG.3

FIG.4

FIG.5

FIG.6.

FIGURE 1 is a perspective view of a jug or the like showing our new design;

FIGURE 2 is a side elevational view;

FIGURE 3 is a top plan view;

FIGURE 4 is an end elevational view looking from the left of FIGURE 1;

FIGURE 5 is a bottom plan view thereof; and

FIGURE 6 is a partial sectional view through the bottom of the jug along lines 6—6 of FIGURE 2.

The dominant features of our design reside in the portions shown in full lines.

The side of the jug opposite that seen in FIG. 2 is a mirror image of the side shown without the measurement markings. The end opposite that seen in FIG. 4 is plain and unornamented.

We claim:

The ornamental design for a jug or the like, substantially as shown and described.
